MICROWAVE OVEN AND CABINET COMBINATION

Gordon J. Waligorski, Lombard, Ill., assignor to Culitron Inc., Chicago, Ill.

Filed Oct. 13, 1972, Ser. No. 297,444

Term of patent 14 years

Int. Cl. D7—04

U.S. Cl. D7—128

FIG. 1

FIG. 4FIG. 2*FIG. 3

The following is a specification, reference being had to the accompanying drawings, forming a part hereof in which:

FIG. 1 is a perspective view of a microwave oven and cabinet combination.

FIG. 2 is a front elevational view thereof;

FIG. 3 is a side elevational view thereof; and

FIG. 4 is a top view thereof.

The undisclosed rear of the oven and cabinet unit are substantially flat and unornamented.

I claim:

The ornamental design for a microwave oven and cabinet combination, as shown and described.
